Primary Examiner — Clare E Heflin(74) *Attorney, Agent, or Firm* — Whyte Hirschboeck Dudek SC(57) **CLAIM**

The ornamental design for a light fixture, as shown and described.

DESCRIPTION

FIG. 1 is a bottom perspective view of an embodiment of a light fixture;

FIG. 2 is a top perspective view thereof;

FIG. 3 is a bottom plan view thereof;

FIG. 4 is a top plan view thereof;

FIG. 5 is a left side elevation view thereof;

FIG. 6 is a right side elevation view thereof;

FIG. 7 is a front elevation view thereof; and,

FIG. 8 is a rear elevation view thereof.

The broken lines of FIGS. 1-8 illustrate portions of the light fixture that form no part of the claimed design.
